UNITED STATES PATENT OFFICE.

IRVIN W. DAVIS, OF SOUTH MILWAUKEE, WISCONSIN, ASSIGNOR TO THE MIDLAND COMPANY, OF SOUTH MILWAUKEE, WISCONSIN, A CORPORATION OF WISCONSIN.

DOOR HANGER.

Application filed October 12, 1922. Serial No. 594,104.

To all whom it may concern:

Be it known that I, IRVIN W. DAVIS, a citizen of the United States, and resident of South Milwaukee, county of Milwaukee, and State of Wisconsin, have invented new and useful Improvements in Door Hangers, of which the following is a description, reference being had to the accompanying drawings, which are a part of this specification.

This invention relates to door hangers and more particularly to a door hanger wherein the hanger frame is adjustably mounted with reference to the pulley.

The invention has for its particular object to provide a construction of this type wherein the pulley is revolvably mounted on a spindle, which spindle in turn is mounted on the hanger frame so that frame is capable of longitudinal adjustment. The construction about to be described provides means for fixing the pulley onto the spindle so as to prevent an axial displacement of the pulley relatively to the spindle, at the same time permitting the desired adjustment of the hanger frame relatively to the spindle.

The novel construction, combination and arrangement of parts wherein this desired object is efficiently accomplished will be made more apparent as the description proceeds, especially when considered in connection with the accompanying drawings.

In the drawings:

Figure 1 is a front elevation of a hanger constructed in accordance with this invention;

Fig. 2 is a vertical sectional view taken on the plane indicated by line 2—2 in Fig. 1, the same being shown on an enlarged scale;

Fig. 3 is a fragmentary section taken on the plane indicated by line 3—3 in Fig. 2;

Fig. 4 is a fragmentary section taken on the plane indicated by line 4—4 in Fig. 2; and,

Fig. 5 is a fragmentary view of a detail of construction.

Referring now more particularly to the drawings wherein like reference characters indicate like parts throughout, it will be seen that there is illustrated a portion of a sliding door 10 and a door frame 11, to which is secured a rail or track 12.

A door hanger frame 13 is secured to the

door by means of bolts 14 or the like. The upper end of the hanger frame 13 is provided with an outwardly extending portion 14', thereby providing a space which is spanned by a spindle 15, externally threaded at one end thereof for engagement with the hanger frame 13. The reduced end 16 of the spindle extends through the extension 14' of the hanger frame.

The threaded portion 15 of the spindle terminates in a shoulder 17, and adjacent this shoulder and surrounding the reduced portion 16 is a sleeve 18 provided with extensions 19 and 20 at the ends thereof.

The sleeve 18 is secured against axial displacement relatively to the spindle 15 by a pin 21 at one end thereof, and a cotter pin 22 at the other end thereof, which pins extend through openings formed transversely of the spindle 15. A collar or washer 23 surrounds the spindle 15 and bears on its one side against the shoulder 17. This collar is provided with recesses 24 for accommodating the pin 21, and with the recesses 25 for accommodating the projections 19 of the sleeve 18.

Disposed adjacent the other end of the sleeve 18 is another collar or washer 26, this collar being provided with a hub portion 27, see particularly Figs. 3 and 5. The hub portion 27 of the collar 26 is provided with recesses 28 for accommodating the cotter pin 22, and with recesses 29 for accommodating the projections 20 of the sleeve 18.

Revolvably mounted on the sleeve 18 is a pulley 30. This pulley is provided with a hardened steel bushing 31, and interposed and between this bushing and the sleeve 18 are a plurality of roller bearings 32. Thus the pulley 30 is freely revolvable about the sleeve 18 which is fixed to the spindle 14 by means of the washers and pins before mentioned.

Longitudinal adjustment of the frame 13 is accomplished by inserting a tool into the recess 33 and rotating the spindle, whereby the same may longitudinally displace the frame 13 to adjust the frame 13 relatively to the pulley 30. For locking the spindle 15 after adjustment of the frame 13, there is provided a collar 34 through which is threaded a lock bolt 35, which impinges against the frame 13, see particularly Fig. 2. A second lock bolt 36, threaded through

the collar 34 impinges against the spindle 15 and also assists in locking the same in its position.

From the foregoing it will be immediately apparent to those skilled in the art that there is provided a hanger for sliding doors and the like, in which the hanger frame is adjustable relatively to the pulley. The particular construction described furthermore provides means for mounting the pulley on the spindle and at the same time preventing any relative displacement between the pulley and the spindle.

The construction of the parts and the manner of assembling is such that they may be disassembled with facility in order that worn or broken parts may be quickly replaced.

While the particular arrangement described and illustrated herein represents one physical embodiment of the invention, it is not intended that this invention be unnecessarily limited but reservation is made to make such changes in the details of construction as may come within the purview of the accompanying claims.

Having thus described the invention what is claimed is:

1. In an arrangement of the class described, a hanger frame, a longitudinally adjustable spindle mounted in said frame, means for locking said spindle in its adjusted positions, a pulley mounted on said spindle and means for locking said pulley on said spindle to prevent axial displacement.

2. In a door hanger, a frame, a spindle mounted in said frame, means for longitudinally adjusting said spindle, a pulley revolvably mounted on said spindle and means for preventing axial displacement of said pulley.

3. In a door hanger, a frame, a spindle mounted in said frame, a sleeve carried by said spindle, a pulley mounted on said sleeve, collars on said spindle and engaging said sleeve, and locking pins engaging said spindle and collars for preventing rotation of said sleeve and axial displacement of said pulley.

4. In a door hanger, a frame, a spindle

mounted in said frame, means for longitudinally adjusting said spindle, a sleeve carried by said spindle, a pulley mounted on said sleeve, and collars on said spindle and engaging said sleeve for preventing rotation of said sleeve and axial displacement of said pulley.

5. In a hanger for doors, a hanger frame, a spindle mounted in said frame, a sleeve on said spindle, said sleeve having projections on its ends, pins passing through said spindle adjacent each end of said sleeve, a pulley mounted on said sleeve and collars carried by said spindle and provided with recesses for accommodating said sleeve projections and said pins whereby said sleeve will be prevented from axial rotation and said pulley will be locked against axial displacement but permitted to revolve on said sleeve.

6. In a hanger for doors, a hanger frame, a spindle mounted in said frame, means for longitudinally adjusting said spindle, a sleeve on said spindle, said sleeve having projections on its ends, pins passing through said spindle adjacent each end of said sleeve, a pulley mounted on said sleeve and collars carried by said spindle and provided with recesses for accommodating said sleeve projections and said pins whereby said sleeve will be prevented from axial rotation and said pulley will be locked against axial displacement but permitted to revolve on said sleeve.

7. In a hanger for doors, a hanger frame, a spindle mounted in said frame, a sleeve on said spindle, said sleeve having projections on its ends, pins passing through said spindle adjacent each end of said sleeve, a pulley mounted on said sleeve, roller bearings interposed between said sleeve and pulley, and collars carried by said spindle and provided with recesses for accommodating said sleeve projections and said pins whereby said sleeve will be prevented from axial rotation and said pulley will be locked against axial displacement but permitted to revolve on said sleeve.

In testimony whereof I affix my signature.

IRVIN W. DAVIS.
